ADVANCING REEL

**Paul Morrison Cole, Wilmington, Del., assignor
to E. I. du Pont de Nemours & Company, Wil-
mington, Del., a corporation of Delaware**

Application May 21, 1949, Serial No. 94,541

6 Claims. (Cl. 28—71.7)

1

This invention relates to the provision of apparatus for continually processing shaped articles. More particularly it relates to advancing and storing shaped articles.

By "shaped articles" is meant yarns, threads, monofils, ribbons, strands and the like. While the discussion below pertains in the main to the use of the apparatus of this invention in the continuous spinning and processing of synthetic filaments, it is understood that the apparatus described herein may be employed wherever a shaped article is to be advanced or stored.

It is well-known that yarn may be advanced in the form of a helix upon a variety of reels. These reels usually involve a considerable number of moving parts. A typical example is the reel in which yarn carrying bars move outward into contact with the yarn, then forward carrying the yarn in this movement, then inward out of contact with the yarn and finally backward to repeat position. Commercial use of advancing devices hitherto known, such as the illustrated reel, involves a large number of units and considerable maintenance cost. Production in both items is highly desirable. The desired results cannot be obtained through the use of skewed reels because there is a limitation on their length due to the interference between non-parallel bars.

An object of this invention is to provide a new advancing device and process. Another object of this invention is to provide an advancing device which involves simple construction and relatively few moving parts. A further object is the provision of an advancing device in which the article after contacting the device automatically advances in a helical path on the device. A still further object is the provision of new apparatus and process for advancing, storing and winding shaped articles. Other and additional objects will appear hereinafter.

The objects of this invention are accomplished by winding the shaped article to be processed on a rotating reel comprising two intermeshing circular cages which have slightly separated parallel axes and supporting surfaces formed into a multiplicity of inclined planes resembling saw teeth or, in effect, bars equipped with rounded, saw-tooth edges. One set of bars is mounted concentrically, the other eccentrically to the axle. The teeth carried on each arm or bar are out-of-phase with those carried by either adjacent bar. The arms on the concentrically mounted set are so positioned that each arm in the set is always between two arms of the eccentrically mounted set and vice versa. One set can, in its rotation, cause

2

the other to rotate or both sets may be driven by the same means, for example, by a rotating axle.

As the two sets rotate as a unit, a given point on the shaped article, assuming string-up has been accomplished, passes from the depression in one saw-tooth into a depression of the succeeding saw-tooth in the adjacent arm. This process is repeated until the yarn has advanced from one end of the reel to the other. The reel is self-advancing; the helical, lateral advancement of the yarn or shaped article is automatic. The teeth on the two intermeshing cages are so arranged that the teeth on a bar of one cage lead the teeth of the preceding bar on the other cage by one-half the tooth pitch. Rotation of the reel causes the yarn or shaped article being processed to be picked up by each cage once in every 180° rotation. The inclined slope of the teeth results in the helical, lateral advancement of the article because the slipwise forward movement to the roots of successive teeth is the path of least resistance.

This invention will be more fully understood by reference to the following illustrative figures in which like numbers refer to like parts and in which:

Figure 1 is a side elevation of the reel with the eccentricity in the vertical plane,

Figure 2 is a front end view,

Figure 3 is a detail showing the relationship of several teeth on two adjacent bars and the yarn ends thereon;

Figure 4 is a sectional view taken on line 4—4 of Figure 2 and

Figure 5 is a sectional view taken on line 5—5 of Figure 1.

Referring to the figures, an axle 1 is rotatably mounted in a support 2 and spindle 20 by any conventional means. Spindle 20 may act as the sole support if suitably attached. While the figures show and the description is concerned with a cantilever construction, the reel may be supported at both ends, if desired. For ease of string-up and for economy, the cantilever construction is preferred. The axle 1, so mounted and rotated by a motor not shown, has mounted on it an inner cage 3 and an outer cage 4. The one cage (inner) is mounted concentrically to an axle or shaft 1 and the other cage (outer) is mounted eccentrically, as shown in Figure 5, or vice versa. In either construction, the axes of the two cages lie parallel and relatively close together. The concentric cage has at its outer extremity a plurality of bars 12 mounted on member 7, these bars carrying saw-teeth or ser-

rations 13. The eccentric cage has a ring 8 at its outer end and at its inner end a support 9. Support 9 with co-supporting members 10 and 11 are rotatably mounted on spindle 20 and hold bearing 18 in place laterally. These can be seen in Figure 4. On the eccentric cage similar bars 14 are mounted on the ring 8 and support 9. These saw-tooth bars are shown in Figures 1 and 4. The bars 12 on cage 3 and bars 14 on cage 4 are interdigitated. The intermeshing of these bars can be seen in Figures 2 and 5, for example.

As shown in Figure 4, the member 7 supporting the bars 12 of concentric cage 3 is driven by shaft 1 by any convenient locking means, as, for example, key 15. The cage 3 is driven thereby by axle 1. The outermost end of shaft 1 is threaded and member 7 is held on the shaft by means of lock washer 16 and lock nut 11. The eccentric cage 4, composed of outer ring 8 connected to inner supports 9, 10 and 11 by saw-tooth bars 14, is rotatably mounted by bearings 18 and needle bearings 19 on spindle 20. This spindle acts as the support for both cages. It does not rotate and bearings 21 and 22 are provided to enable shaft 1 to rotate without driving spindle 20. Concentric cage 3, composed of member 7 carrying saw-tooth bars 12, is mounted directly on axle 1 and is mounted so that it can rotate about spindle 20 by means of bearings 21 and 22. The various parts are bolted together by bolts and nuts as shown at 23 in Figure 4. A protective cap 24 fastened by any convenient means such as a spring clip is placed on the outermost end of concentric cage 3. At the innermost end is a diaphragm seal 25 for exclusion of processing liquids from the bearings. This is held in place by any convenient means, as, for example, by spring 6. The diaphragm seal may be made of any material resistant to the processing liquids. Phenolic resins can be used, for example, in making the diaphragm.

Rotation of axle 1 causes concentric cage 3 to rotate. As the bars 12 on this cage rotate one of them will eventually strike one of the bars 14 on eccentric cage 4. Such a point of contact is shown at 26 in Figure 5. This contact will cause cage 4 to rotate.

The yarn wrap 27 can be seen in Figure 1. It is helical in shape. The thread 28 is fed to the rotating reel at a point near the support and with the reel rotating in a clockwise direction the thread advances to the outer part of the reel. The yarn will move from the innermost part to the outermost part regardless of the direction of rotation if the major slope of the teeth faces the outer end. Opposite movement is obtained by using teeth with a slope in the opposite direction. A given wrap of yarn on the reel is not exactly circular, due to the eccentricity. This can be seen in Figure 5 where the dotted line 29 shows the yarn resting only on the bars of the concentric cage at certain areas, only on the bars of the eccentric cage at other points, and on both at still other positions. This can be seen also in Figure 1 as to the whole yarn wrap which rests in the roots of the teeth on certain bars and on the slopes of the teeth of other bars and, at certain areas is not in contact with any bar, that is, areas between two consecutive yarn supporting bars of one cage. As the reel is rotating, one cage is alternately picking the yarn wrap off the other cage and advancing the yarn because of the difference in pitch of the teeth. In Figure 3 this advancement can be seen. The 75

teeth 30 shown by the solid line are on a bar, say 12, moving away and downward. The thread ends 31 are resting on the roots of these teeth. The teeth 32, marked by the dotted lines, are on a bar, say 14, following the former but coming upward. In these movements each thread end 31 will land on the slopes of teeth 32 and as rotation continues they leave the teeth 30 entirely as bar 12 drops away and finally the ends rest in the roots of teeth 32. Since the roots of 32 are closer to the outermost part or unsupported end of the reel than the roots of 30, the yarn has advanced. Each succeeding bar causes the process to be repeated.

In any modification the reel is constructed so that the working parts never come in contact with the treating liquid. Only the yarn supporting saw-tooth bars come into contact with the liquids.

The various parts of the reel are constructed of any material resistant to the action of the liquids applied to the yarn or shaped article being treated. Such materials include, stainless steel, aluminum, Monel metal, various synthetic resins and the like. Generally, the reels are made of light weight materials.

The reel may be of sufficient length to allow for complete processing of the shaped article on one reel. For example, if rayon is being produced, the thread may come directly from the spinning bath to the reel where the following treatments, washing, desulfuring, rewashing, bleaching, rewashing, finishing and drying can be applied successively as the thread advances. Appropriate catch pans and conduits can be placed beneath the reel to recover processing liquids. It is also possible to carry out different processing steps on different, successive reels. Since the bars on the two cages are parallel, it is possible to extend them to great lengths and thereby gain maximum mechanical efficiency. Long reels are, accordingly, preferred.

As shown in Figures 1, 3 and 4 the teeth on the bars of the eccentric cage are out of phase with those on the bars of the concentric cage. The difference is, in general, one-half the tooth pitch. While this difference may vary, it is preferred that the difference be as shown because the yarn follows in the helical path very readily. Similarly, the length of the vertical edge of the tooth and the length of the sloping edge may be varied considerably depending upon thread size, tension to be applied, etc. The teeth may be rounded in either a convex or concave fashion. The difference in pitch and shape of the teeth, however, must be such that the yarn advances. That is, any construction in which a yarn end could fall on the apex of a tooth and thereby fall in either direction on the principal bar must be avoided. Likewise, the distance of one cage axis from the other may vary, but the eccentricity must be great enough to cause the threads to clear the crowns of one set of teeth at each extreme position. Excess eccentricity other than to provide a factor of safety handicaps the design. In general, the axes lie close together.

It is possible, also, to use one or more smooth edge bars instead of the saw-toothed bars on either cage. For helical advancement, the saw-tooth bars, the tooth displacement and the described eccentricity of the cages are required, of course, but the degree of advancement, amount of tension on the yarn, etc. may be varied by use of an occasional smooth surfaced bar in either 70 cage. Further, either or both of the cages bear-

ing the saw-tooth bars may be tapered in either direction. For processing under very low tensions, the bars are tapered downwardly in the direction of advancement. Generally, the construction of the reel inherently permits processing under low tensions and tapering is not essential. For stretching or for processing under increased tension, it is necessary to taper the bars upwardly in the direction of advancement. The use of saw teeth on an intermeshing reel with skewed axes permits a tapered construction for stretching or relaxing to a higher degree than has been heretofore possible with such reels.

The apparatus and methods of this invention are advantageous in that there is a minimum of moving parts. The yarn or shaped article advances in a helical path in a "self-advancing" manner. The reel is of simple construction and it may be rotated at various speeds to accommodate articles of different sizes. Any of the well-known spinning procedures, such as the dry, wet or melt spinning techniques, may be used in connection with this apparatus. A series of reels of this invention may be used in tier or any other such fashion. Successive reels may be so constructed that different tensions are applied on the article being processed. One outstanding advantage of this invention lies in the fact that the yarn may be advanced without applying tension on the yarn. Only a very low tension need be used and this tension approaches that exerted on the yarn by the centrifugal force. Further, the reel is self-threading; if a yarn end is thrown around the revolving reel, the yarn wrap forms automatically. If desired, the end may carry an adhesive. Still further, the simple construction of the reel of this invention permits the ready use of reels of substantial size and hence of great advancing and storing capacity.

By the apparatus and processes of this invention yarns and the like of any material may be continually advanced and stored and processed during advancing and storing. Such materials include natural materials, such as cotton, as well as synthetics such as regenerated cellulose, cellulose acetate, polyamides, polyacrylonitriles and the like.

Any departure from the procedure described herein which conforms to the principles of the invention is intended to be included within the scope of the claims below.

I claim:

1. A reel for advancing a yarn in a general helical path comprising two rotatable circular cages, each comprising a plurality of parallel mounted bars; said cages being mounted on offset axes parallel with each other and with said

bars; said bars being intermeshed; serrations on the said bars, the serrations on any bar of one cage being out of phase with those on adjacent bars on the other cage.

5 2. A reel in accordance with claim 1 in which the difference in phase of said serrations amounts to about one-half the pitch of said serrations.

3. A reel for advancing a yarn in a general helical path comprising an outer circular cage, bearing yarn supporting surfaces in the form of a plurality of planes resembling saw-teeth; an inner circular cage mounted on an axis parallel and offset to the axis of said outer circular cage, bearing yarn supporting surfaces in the form of a plurality of planes resembling saw-teeth out of phase with said surfaces on said outer cage; and driving means for rotating the inner cage concentrically and the outer cage eccentrically with respect to the axis of the inner cage.

10 20 4. A reel in accordance with claim 3 in which the difference in phase of said yarn supporting surfaces amounts to about one-half the pitch of said surfaces.

5 25 5. A reel for advancing a yarn in a general helical path comprising a driven axle; a spindle journaled thereon; an outer circular cage rotatably mounted on said spindle, along an axis common to that of said spindle, said common axis being parallel and offset to the axis of said axle; a plurality of serrated bars on the periphery of said outer cage; an inner circular cage mounted to be driven by said axle, its axis of rotation being common to that of said axle and a plurality of serrated bars on the periphery of said inner cage which intermesh with said bars on said outer cage, the serrations on a bar of the inner cage being out of phase with the serrations on adjacent bars of the outer cage.

30 35 40 6. A reel in accordance with claim 5 in which the difference in phase of said serrations amounts to about one-half the pitch of said serrations.

PAUL MORRISON COLE.
